WILLIAM O. BARNES, OF LEOMINSTER, MASSACHUSETTS.

MACHINE FOR GRINDING FORMED CUTTERS.

1,373,587.

Specification of Letters Patent.

Patented Apr. 5, 1921.

Application filed October 25, 1919. Serial No. 333,162.

To all whom it may concern:

Be it known that I, WILLIAM O. BARNES, a citizen of the United States, residing at Leominster, county of Worcester, State of Massachusetts, have invented an Improvement in Machines for Grinding Formed Cutters, of which the following is a specification.

This invention relates to grinding machines, more especially, although not exclusively, to machines for grinding formed cutters, examples of which machines are shown and described in Letters Patent Nos. 1,196,420 and 1,236,898, issued to me August 29, 1916, and Aug. 14, 1917, respectively.

The invention has for its objects to provide an improved grinding machine in which the cutter is held stationary and the grinding wheel is moved relative thereto under the control of a templet; to provide a machine capable of grinding cutters on their own arbors, which results in great convenience and saving of time, while producing very accurate results; to provide convenient means for holding the cutters to be ground; to provide simple and effective templet supporting and clamping means and means for adjusting said templet relative to the cutter; to provide improved means for grinding off the back part of the profile face of a cutter tooth when desired; and to provide improved means for dressing or truing the grinding wheel.

The foregoing and other objects of the invention, together with means whereby the same may be carried into effect, will best be understood from the following description of one illustrative form thereof shown in the attached drawings, wherein:

Figure 1 is a plan view of the machine, the grinding devices being omitted, and the templet being shown in dotted lines;

Fig. 2 is a front elevation thereof, a cutter (shown in dotted lines) being shown in position to be ground;

Fig. 3 is an end elevation thereof;

Fig. 4 is a sectional view on the line 4—4 of Fig. 3 looking in the direction of the arrows;

Fig. 5 is an enlarged sectional view on the line 5—5 of Fig. 1;

Fig. 6 is a plan view of the portable grinding wheel carrier;

Fig. 7 is a sectional view on the line 7—7 of Fig. 6;

Fig. 8 is a side elevation of said grinding wheel carrier;

Fig. 9 is a section on the line 9—9 of Fig. 6;

Fig. 10 is a section on the line 10—10 of Fig. 8;

Fig. 10^a is a section on the line 10^a—10^a of Fig. 9;

Fig. 11 is a plan view of an improved form of wheel dressing device;

Fig. 12 is a section on the line 12—12 of Fig. 11, the wheel dressing device being shown in the act of truing the grinding wheel;

Fig. 13 is a side view of the grinding wheel illustrating the operation of grinding the profile face of the tooth of a cutter;

Fig. 14 is a view similar to Fig. 13 showing the parts adjusted to grind off the back edge of the profile face of a tooth in order to provide clearance.

In said drawings the numeral 15 indicates the machine base, which is preferably of such a height as to bring the table supported thereby to a height convenient for the operator. This base carries two upwardly extending brackets 16 carrying oppositely disposed center bars 17, preferably provided with detachable centers 17' between which the work is rotatably supported. The center bars are transversely adjustable by means of adjusting screws 18 conveniently operated by hand wheels 19 and are clamped in adjusted position by any suitable means, such as bar clamps 20. The base 90 supports a plane work table 21, pivotally connected thereto as by pivot bars 22, and adjustable on said pivots by a lifting screw 23. Near its rear edge the work table carries a templet 24, the forward edge of which 95 has the configuration of the profile edge of the cutter to be ground. The forward edge of the templet may be supported on the surface of the table by bosses 25 formed on said templet, and the rear part of said templet rests upon a step 26 and engages and is positioned by a shoulder 27, said step and shoulder being both formed on the table 21. The templet is held in this position by a number of clamp rods 30 normally forced 100 upwardly by coil springs 31 and provided with inclined recesses 32 receiving the inclined ends of clamping bars 33, which may be forced rearwardly when desired by clamp screws 34 in the forward edge of the table. 110

Unlike the machines shown in the prior patents above referred to, the grinding wheel of the present machine is movable over the work table, and to this end there is provided a portable wheel carrier carrying an electric motor or other source of motive power for rotating the wheel. This carrier also supports a guide pin which coacts with the templet for properly guiding the grinding wheel along the edge of the cutter tooth. The wheel carrier comprises a base 40 mounted on adjustable feet 41 and carries an adjustable slide 42 formed with a hood or guard 38 supporting between its opposite sides a shaft 44 upon which the grinding wheel 43 is rotatably mounted. As shown in Fig. 7, the shaft 44 is provided with a sleeve 37 which is clamped between the opposite sides of the hood 38 by means of a nut 36 on said shaft. The sleeve 37 carries two inner bearing races 45 slidably mounted thereon and disposed concentric with outer bearing races 46 carried by the wheel hub 39. Bearing balls 46' are mounted between the races, and a coil spring 47 surrounds the sleeve 37 and bears against the inner bearing races 45 and serves to hold them apart. As the movement of the outer races is limited by the hub, this spring serves to take up any looseness due to improper fitting or wear in the races and insures a free and steady running of the wheel. The hub of the grinding wheel is formed with a portion 48 which serves as a belt pulley and receives a belt 49 the other end of which co-operates with a belt pulley 50 carried by the shaft of a motor 51 supported on the slide 42. Any suitable conductor (not shown) may be used for supplying energy to the motor, and it will be obvious that the wheel carrier can readily be moved over the surface of the table for bringing the wheel into proper relation with the article to be ground. In order to facilitate this it may be desirable to provide said carrier with a suitable handle 58. The wheel slide 42 is slidably mounted upon the base 40 by means of a dove-tail 53 on the slide which is received in a dove-tailed groove 52 in the base. The slide may be adjusted forwardly or rearwardly on the base by means of an adjusting screw 55 journaled in said slide and having threaded engagement with a lug formed on a bracket 54 bolted or otherwise secured to the base. The adjusting screw is preferably provided with a hand knob 56 which may carry a graduated scale co-operating with a fixed indicator on the slide. After having been properly adjusted, the parts are clamped in position by a gib screw 57. The sliding movement of the wheel slide is in a plane inclined slightly to the horizontal. This is for the same purpose as in previous machines, the reason therefor being fully explained in Patent No. 65 1,236,898, above referred to.

The forward end of the base 40 is provided with a vertical notch 59 (see Fig. 10). Received in this notch is the lower end of a rest rod 60, a truing guide pin 62, and a guide pin 63. Between the rest rod and the truing guide pin is normally inserted a distance piece 61 also received in the notch. The parts 60, 62 and 63 are held in the notch by clamp plates 64, 65 and 66, respectively, which plates are held in clamping position by set screws 67, 68 and 69, respectively, said set screws having conical ends which co-operate with openings in said plates to retract said plates into clamping engagement with said parts 60, 62 and 63. 80

In order to obtain the required clearance angle in grinding a cutter, it is necessary to perform the grinding operation at a point below the horizontal diameter of the grinding wheel, and the rest rod is so dimensioned as to position its upper end at the desired point, in order to support the cutter tooth being operated on at the required distance below the horizontal diameter of the grinding wheel. The peripheral edge of the grinding wheel is so shaped that the curvature of a horizontal section through the wheel at the top of the rest will exactly correspond with the curvature of the guide pin 63 and will lie in exact vertical alinement therewith. It will be obvious therefore that, if the wheel carrier be moved sidewise across the table with the guide pin in contact with the templet, the path of the grinding point will be a reproduction of the forward edge of the templet and will lie above it in exact perpendicular alinement with respect to the templet and work table. In order to secure the proper adjustment of the work table for obtaining the proper relation between the grinding wheel and the cutter tooth, a square is laid on the table with one edge bearing against the templet. The table is then tilted by the table lifting screw 23 until the square just comes into contact with the profile edge of the cutter tooth. 105 110

As the grinding wheel is gradually worn away during the grinding operation, and as its peripheral contour must correspond exactly with the guide pin, there is provided a novel wheel dressing and truing device shown best in Figs. 11 and 12. The truing device comprises a base 72 supported on adjustable feet 73 and carrying a vertical column 74 on which is mounted for vertical adjustment a block 75. The column 74 is provided with a threaded portion 76 to receive a nut 77 located in a notch or recess in the block 75, rotation of said nut serving to vertically adjust said block with respect to the base. The forward foot 73 may be extended to form a dowel pin 78 received in an opening in the bottom of the block 75 for holding the same against rotation on the column 74. Secured to the 125 130

bottom of the block 75, as by screws 79, is a bearing plate 80 formed with a V-shaped notch 81.

The truing of the wheel is done by a suitable dressing tool, preferably a diamond 82 mounted in a diamond carrier 83 which is received in a transverse opening 84 near the upper end of the block 75. The carrier 83 is pressed forwardly by a spring 85 and 10 is clamped in adjusted position by clamp screw 86. An aperture or pocket 87 formed in the block 75 immediately below the diamond serves to collect the material removed from the grinding wheel.

15 The truing of the grinding wheel should take place at approximately its horizontal diameter, as at this point a slight error in the vertical adjustment of the diamond will not result in any appreciable difference in 20 the diameter of the wheel and will, therefore, not cause any appreciable displacement of the operative portion of the wheel with respect to the templet guide surface. During the wheel truing operation the bearing 25 block 80 bears against the truing guide pin 62. This is slightly larger in diameter than the guide pin 63 and is eccentrically and forwardly disposed with relation to it. The axis of the truing guide pin is displaced 30 from the axis of the guide pin a distance equal to the difference between the radius of the grinding wheel and one-half of the horizontal cord of the grinding wheel through the grinding point, for the reason 35 that the truing of the wheel must take place forwardly of the grinding point by this amount.

Means are provided for properly positioning the dressing tool with respect to the 40 bearing block 80, said means, as herein shown, comprising a cylindrical setting rod 90 permanently secured in a bracket 91, preferably permanently secured to the base of the machine, as shown in Fig. 3. The 45 setting rod is clamped in place in substantially vertical position by means of center pins 92 with its axis perpendicular to a substantially horizontal portion 93 of the bracket. This setting rod is of the same 50 diameter at its base as the truing guide pin 62, that being the point at which said rod is engaged by the walls of notch 81 in the truing device. The upper end of the setting rod, with which the diamond makes contact, is of the same diameter as guide pin 63. In order to accurately adjust the dressing tool, the complete truing device is set 55 on the horizontal portion 93 of the bracket and is moved forwardly until the notch 81 60 engages the setting rod, the clamp screw 86 having first been released. The spring 85 will hold the diamond carrier 83 against the upper end of the setting rod, and the tightening up of the screw 86 will serve to clamp 65 said diamond carrier in proper position.

After a cutter has been sharpened a number of times by grinding back the profile face of the teeth, the clearance of the teeth will be lost on account of the inclination of the back edge of the teeth and the consequent widening of the profile face as the teeth are ground down. In order to provide the necessary clearance in such cases and place the cutters in condition for further service, it will be necessary merely 70 to remove the distance piece 61, whereupon the rest 60 will be slightly lowered. The tooth will, therefore, be supported in a somewhat lower position, enabling the grinding wheel to grind away the rear portion of the 75 profile face of the tooth, as will be clear from Fig. 14.

While a preferred embodiment of the invention has been shown and described herein in more or less detail, it will nevertheless 80 be understood that this detailed description is to be considered merely as illustrative and not as limiting, and that changes and modifications in the construction shown and described may be made by those skilled in 85 the art without departing from the invention as defined by the claims hereunto appended.

Having thus described my invention, I 90 claim:

1. A machine of the character described comprising a table, means for supporting the work above said table, a templet in fixed relation to said table, a portable grinder, and a guide pin in fixed relation to and movable with said grinder, said grinder being movable over the surface of said table with said guide pin in engagement with said templet, and said portable grinder and guide pin being in vertical alinement, whereby said work is ground to the shape of the 95 templet.

2. A machine of the character described comprising a table, means for supporting the work above said table, a templet in fixed 100 relation to said table, a portable grinder having a grinding wheel, and a guide pin carried by said grinder in vertical alinement with the operative point in the periphery of said grinding wheel, said grinder being movable over the surface of said table with said guide pin in engagement with said templet, whereby said work is ground to 105 the shape of the templet.

3. A machine of the character described 110 comprising a table, means for supporting the work above said table in fixed relation thereto, a portable grinder movable over said table, and co-operative guiding means carried by said table and grinder for limiting the movement of said grinder toward said work, said guiding means being in vertical alinement with said work supporting means and portable grinder.

4. A machine of the character described 115

comprising a table, means for supporting the work above said table in fixed relation thereto, a portable grinder movable over said table, and coöperative guiding means 5 carried by said table and grinder for limiting the movement of the grinder toward said work, said means comprising a templet carried by one of said parts and a guide pin carried by the other of said parts, and said 10 templet being in vertical alinement with said work supporting means.

5. A machine of the character described comprising a table, means for supporting the work above said table in fixed relation 15 thereto, a portable grinder movable over said table, and coöperative guiding means carried by said table and grinder for limiting the movement of the grinder toward the work, said means comprising a templet carried by said table and a guide pin carried by said grinder, said templet and guide pin, respectively, being in vertical alinement with said work holding means and grinder. 20

6. A machine of the character described comprising a table, means for supporting the work above said table in fixed relation thereto, a portable grinder movable over said table and having a grinding wheel, and coöperative guiding means carried by said 25 table and grinder for limiting the movement of said grinder toward the work, said means comprising a templet carried by said table and a guide pin carried by said grinder, said guide pin being in vertical alinement with 30 the operative point in the periphery of said grinding wheel.

7. A machine of the character described comprising a table, means for supporting the work above said table in fixed relation 40 thereto, a portable grinder movable over said table and having a grinding wheel, and coöperative guiding means carried by said table and grinder for limiting the movement of said grinder toward the work, said means comprising a templet carried by said table 45 and a guide pin carried by said grinder, said guide pin being in vertical alinement with the operative point in the periphery of the grinding wheel and having a curvature corresponding to the curvature of the horizontal section of the wheel periphery at the 50 grinding point.

8. A machine of the character described comprising a support provided with a table, 55 uprights carried by said support, work holding centers carried by said uprights, a portable grinder movable over said table, and coöperative guiding means carried by said table and grinder for controlling the 60 movements of said grinder.

9. A machine of the character described comprising a support provided with a table, 65 uprights carried by said support, work holding centers carried by said uprights, a portable grinder movable over said table, a tem- 130

plet fixed to said table, and a guide pin carried by said grinder and coöperating with said templet.

10. A machine for grinding the profile faces of formed cutter teeth comprising a 70 table, means for supporting a cutter above said table in fixed relation thereto, a portable grinder movable over said table, and coöperative guide means carried by said table and grinder for limiting the movement of 75 said grinder toward said cutter, said means comprising a templet carried by one of said parts, a guide pin carried by the other of said parts, and a rest carried by said grinder for supporting the teeth of said cutter. 80

11. A machine for grinding the profile faces of formed cutter teeth comprising means for supporting a cutter, a grinder, said supporting means and grinder being relatively movable to cause said grinder to 85 operate upon said cutter, and a rest for supporting the teeth of said cutter in proximity to said grinder, said rest being normally fixed with respect to said grinder but being adjustable with respect thereto to vary the 90 point of operative engagement of said cutter with said teeth.

12. A machine for grinding the profile faces of formed cutter teeth comprising a 95 table, means for supporting a cutter above said table in fixed relation thereto, a portable grinder movable over said table, coöperative guiding means carried by said table and grinder for limiting the movement of said grinder toward the cutter, said 100 means comprising a templet carried by one of said parts and a guide pin carried by the other of said parts, a rest for supporting the teeth of said cutter, a distance piece under said rest for positioning it to support 105 the cutter teeth for grinding their profile faces, said piece being removable for permitting the lowering of the rest to support the teeth in position for grinding the back portions thereof. 110

13. A machine of the character described comprising a table having a step and a shoulder, a templet supported on said step against said shoulder and having bosses resting on the surface of said table, clamp rods 115 guided for movement in said table and having notches to receive the edge of said templet, said clamp rods having inclined recesses, clamping bars guided for movement in said table and provided with inclined ends co-operating with the recesses in said rods, and a portable grinder movable over said table 120 and provided with a guide pin coöperating with said templet.

14. A portable grinder, a base therefor 125 having a vertical notch, a rest and a guide pin in said notch, a distance piece between said rest and guide pin, and means for clamping said rest and guide pin in place in the bottom of said notch. 130

15. A portable grinder, a base therefor having a vertical notch, a rest and a guide pin in said notch, a distance piece between said rest and guide pin, and means for 5 clamping said rest and guide pin in place in the bottom of said notch, said means comprising clamping plates formed with apertures to receive said rest and pin, respectively, and clamping screws for retracting 10 said plates.

16. A machine of the character described

comprising a base, a templet, means for supporting work in fixed relation to the templet, a movable grinding wheel carrier, a grinding wheel thereon, a guide pin in 15 alignment with the operative point in the periphery of the wheel, and means for limiting the movement of said grinding wheel carrier to the plane of the templet.

In testimony whereof I affix my signature. 20

WILLIAM O. BARNES.
